WIRELESS SIGNALING SYSTEM.

Application filed November 26, 1920. Serial No. 426,429.

This invention relates to a signaling system and more particularly to an arrangement whereby interaction between a plurality of transmitting circuits of a multiplex station resulting in cross talk may be eliminated.

In any system of multiplex wireless transmission in which two or more modulated carrier waves are impressed upon an antenna system, which comprises either antennæ spaced apart or separate portions of a unitary structure, there is a coupling connection between the several antennæ due to the capacity between each antenna and ground, the capacity between the antennæ, mutual induction between the antenna circuits and the common resistance path of the several antennæ.

In such systems each channel is provided with an amplifier for the modulated carrier current supplied to the antenna with which it is associated, and, owing to the coupling connection described above, voltages are induced in the output circuits of each of the amplifiers included in the other channels when energy is radiated from the antennæ, and as a consequence there is cross-talk.

This coupling resulting in cross-talk, can be eliminated by making the antennæ non-inductive, but this is not very practical owing to the sacrifice of power entailed.

One object of this invention is to prevent cross-talk in a multiplex transmitting system.

Another object is to provide an arrangement whereby the effect of the coupling connection due to the mutual impedance between a plurality of adjacent circuits, may be neutralized with a minimum loss of power.

According to this invention these objects may be accomplished by supplying each amplifier with voltages of proper phase and value to neutralize the undesirable potentials induced in its output circuit by the radiation of modulated current of other carrier frequencies than that supplied to the antenna through the particular amplifier under consideration.

One method of accomplishing these objects and others which will appear as the description proceeds is shown, by way of example, in the attached drawings, in which

Figure 1 shows the invention applied to a system employing two antennæ and Figure 2 illustrates the application of the invention to a transmission system utilizing three antennæ, some features of this arrangement being omitted for the sake of simplifying the drawing and others being schematically shown.

In this disclosure an amplifier, herein shown for illustrative purposes only as of the audion type, is associated with an antenna to supply modulated carrier current of a definite frequency thereto for signal transmission purposes and, by means of compensating circuits, with the antennæ upon which the other signal frequencies are impressed.

The compensating circuits may be either directly or inductively coupled to the antennæ with which they are associated, but provision should be made to regulate the voltage supplied to the amplifiers through these circuits so that it is of just sufficient magnitude to neutralize the induced voltages in their plate circuits. An adjustable coupling between the respective antennæ and the associated compensating circuits may be used for this purpose, though it is obvious that any other method of regulating the voltage fed back may be employed.

As is well known the compensating voltages derived from the different antennæ will not be in phase with the undesirable voltages induced in the plate circuits of the amplifiers, as a result of radiation of signaling current from the other antennæ, and hence, to correct this out-of-phase condition of the voltages fed back, the compensating circuits should include phase adjusting devices each adapted to regulate the phase of the voltage derived from the antenna with which the particular compensating circuit is associated.

For a complete disclosure of the invention reference will now be made to the attached drawings.

Referring to Fig. 1, separate antennæ 1 and 2 are shown, the earth's surface being represented by the line 3—3, to which each antenna is separately grounded. Separate current sources 4 and 5 are adapted to supply modulated current of different carrier frequencies to the antennæ 1 and 2 respectively.

The modulated current supply source 4,

which comprises a source of carrier current, the frequency of which may be represented by f' , and means for modulating it, is connected to the input circuit of the amplifier 7 through the transformer 6. The amplifier is herein shown, for illustrative purposes, only, as a vacuum tube 7 enclosing a heated filament or cathode 8, an impedance control element or grid 9 and a plate 10. Amplified current is supplied to the antenna 1 by the transformer 11, the primary of which is included in the output circuit of the amplifier and the secondary of which is included in the antenna circuit.

The antenna 2 is supplied with amplified modulated carrier current of a frequency f^2 through amplifier 14 and the transformer 12, the primary winding of the latter being included in the plate circuit of the tube while its secondary winding is connected in the antenna circuit. Modulated current from source 5 is supplied to the input circuit of the said amplifying tube through the transformer 13. While separate sources of current supply are herein shown a single source adapted to supply currents of different frequencies may be used. Moreover, as the method of connecting the amplifier and antenna is not an essential feature of the invention, any other method of interconnecting them may be employed.

The capacitive coupling between the two antennæ 1 and 2 is indicated by the circuits 15, shown in dotted lines connecting them, which includes the condensers C ; and the capacity between each antenna and ground is represented by condensers C' and C'' which are indicated as connected between said antennæ and ground by the dotted circuits 16 and 17, respectively.

Due to these capacitive couplings, mutual induction and the ground connection between these antennæ a voltage will be induced in the plate circuit of the amplifier 7 when signaling current is transmitted from antenna 2 and in like manner radiation of energy from antenna 1 will induce a voltage in the plate circuit of the amplifier 14. When the antennæ are in operation simultaneously an induced voltage will be present in the plate circuits of both amplifiers and consequently there will be cross-talk, with the attendant confusion of signals and impairment of their quality.

Inductively associated with the secondary winding of the transformer 11 is a winding 18 shunted by a condenser 19, this latter combination constituting a phase adjusting device, which is connected by the conductors 20 to the grid circuit of the amplifier 14. In a similar manner the secondary of the transformer 12 has a phase adjusting circuit 21-22 associated with it which is connected to the grid circuit of the amplifier 7 by the conductors 23.

In case it is found necessary or desirable to increase the amplitude of the oscillations fed back to the grid circuits of the amplifiers may be increased before being impressed thereupon by means of auxiliary amplifiers 24, adapted to be included in each of the connecting circuits 20 and 23 by means of the switches 28.

Referring to Fig. 2 in which the invention is shown applied to a transmitting station which involves the use of three antennæ, the amplifiers are shown schematically while the sources of modulating current of different frequencies have not been illustrated. It is to be understood that each amplifier is supplied with a modulated current of different frequency from that supplied to the others and that the amplifiers are associated with said sources in any desired manner, one of which is shown in Fig. 1.

The coupling connection between the antennæ AN , AN_1 , and AN_2 and between the separate antennæ and ground are indicated by the dotted lines extending between these antennæ and from the separate antennæ to ground, which include condensers C_1 to C_7 . The capacitive coupling between the antennæ AN and AN_2 is represented by condensers C_1 , between the antennæ AN and AN_1 by the condensers C_2 and between the antennæ AN_1 and AN_2 by the condensers C_3 . The coupling between the antenna AN and ground is represented by the condenser C_4 and part of C_5 ; that between AN' and ground by parts of condensers C_5 and C_6 and between antenna AN_2 and ground by part of condenser C_6 and condenser C_7 .

As herein shown, a compensating voltage is derived from the antenna AN which, after being adjusted by the phase regulating device PA , flows through the compensating circuit 40 and the branch circuits 30 and 31 to the grid circuits of the amplifiers AM_1 and AM_2 , respectively.

In like manner voltage derived from antenna AN_1 has its phase adjusted by the phase regulating device PA_1 , flows through the compensating circuit 41 and through the branch circuits 33 and 34 which are respectively connected to the grid circuits of the amplifiers AM and AM_2 , and potential derived from the antenna AN_2 , after having its phase adjusted by the phase regulating device PA_2 , traverses the circuit 42 and the branch circuits 35 and 36 to the grid circuits of the amplifiers AM and AM_1 , respectively.

As described, it will be seen that this system includes a conductive path between each of the phase adjusting devices and the amplifier associated with the same antenna through the associated compensating and branch circuits. In order to prevent the transfer of voltage over this path a unidirectional conductive device 37, herein shown by way of example as of the vacuum tube type, is included in each branch circuit.

Further description of these devices, other than to state that they must be operated so that no modulation of the voltage traversing one branch by that flowing through the branch connected to the same amplifier grid circuit should take place, is thought to be unnecessary since the operation of such devices is now well understood.

To avoid positive polarization of the grid elements of the main amplifiers, the output circuit of the unidirectional devices should be so connected to the input circuits of the main amplifiers that no direct current can flow thereto from the plate sources for these devices. One simple method of accomplishing this would be to couple the plate circuits of the unidirectional devices to the input circuit of the main amplifiers inductively, as shown at 38.

Line 3—3, as in Fig. 1, indicates the surface of the earth to which the antennæ are separately grounded.

From the preceding description it will be obvious that by a mere duplication of the compensating circuits, each provided with a properly adjusted phase shifting device connected between the antennæ and the amplifiers in the manner described above, the principles of this invention can be applied to a multiplex transmitting system adapted for use with any number of signaling channels.

One of the essential features of this invention is that voltages only are fed back through the compensating circuits, that the amplifying factor of the main amplifiers is utilized to increase the amplitude of these voltages, with the result that the power diverted from the supply sources for the several antennæ is a minimum and, as there is no energy transferred through the compensating circuits, the losses in these circuits are negligible. Furthermore, this result is accomplished by means of the elements normally used for signaling purposes.

In case a small auxiliary amplifier is used in the compensating circuits as hereinbefore suggested the additional power required is relatively small, since it is merely that supplied by the plate circuit battery of said auxiliary amplifiers.

While a particular arrangement involving certain elements and connections has been specifically described in this specification, in order to disclose completely and clearly the nature of the invention, it is to be understood that this invention is not limited thereby but solely by the scope of the appended claims.

60 What is claimed is:

1. An electric system comprising a plurality of adjacent transmission circuits, means including an amplifier for supplying an alternating current to each of said transmission circuits, and means including said

amplifiers for transferring energy between said circuits for compensating for interaction therebetween.

2. A multiplex wireless transmitting system comprising a pair of antennæ, a signal channel associated with each antenna including an amplifier and means associated with each antenna for supplying a voltage to the input circuit of the amplifier associated with the other antenna for compensating for interaction between said antennæ.

3. A multiplex wireless transmitting system comprising a plurality of antennæ, a signal channel associated with each antenna including an amplifier and means associated with each antenna for supplying voltages to the input circuits of the amplifiers associated with the other antennæ for compensating for interaction between said antennæ.

4. A wireless transmission system comprising a plurality of antennæ, an amplifier associated with each antenna for supplying signal current thereto, and means including said amplifiers for compensating for interaction between said antennæ.

5. A wireless signaling system including a plurality of antennæ, a signal circuit associated with one of said antennæ including an amplifier for transmitting energy thereto, and means associated with the other of said antennæ for supplying a voltage to the input circuit of said amplifier for compensating for interaction between said antennæ.

6. A wireless signaling system including a plurality of antennæ, signal circuits associated with said antennæ, and means including an amplifier for transmitting energy from one antenna to the signal circuits of the other antennæ for compensating for interaction between said antennæ.

7. A multiplex wireless transmitting system comprising a pair of antennæ and a signal channel associated with each antenna including an amplifier, means associated with each antenna supply source for deriving a voltage therefrom and means including a phase adjusting device for connecting said deriving means to the input circuit of the amplifier associated with the other antenna.

8. A multiplex wireless signal transmitting system comprising a plurality of antennæ and a signal channel associated with each antenna including an amplifier, means associated with each antenna supply source for deriving a voltage therefrom and means including a phase adjusting device and a unidirectional conducting device for connecting said deriving means to the input circuits of the amplifiers associated with the other antennæ.

9. A multiplex wireless transmitting system comprising a pair of antennæ, a plurality of amplifiers, and a plurality of sources of modulated carrier current of dif-

ferent frequencies each adapted to supply a signal current through one of said amplifiers to a selected antenna, and circuits associated with each antenna adapted to supply 5 a voltage to the input circuit of the amplifier associated with the other antenna for compensating for interaction between said antennæ.

10. A wireless signal system comprising a pair of antennæ, a signal channel including an amplifier associated with each antenna, means for deriving a voltage from each antenna and means including an amplifying device for applying said voltage to neutralize an undesirable voltage induced in the plate circuit of the amplifier associated with the other signal channel.

11. A wireless signal system comprising a pair of antennæ, a signal channel including an amplifier associated with each antenna, and a circuit interconnecting each antenna and the amplifier included in the other signal channel for transferring energy to compensate for interaction between said antennæ, said circuits each including a phase regulating device and an amplifier.

12. A wireless signal system comprising a plurality of antennæ, a signal channel including an amplifier associated with each antenna and circuits connecting each antenna with the amplifiers included in the other signal channels for transferring energy to compensate for interaction between said antennæ, each circuit including a phase regulating device and an amplifier.

13. An electric system comprising a plurality of adjacent transmission circuits, an alternating current supply source for each transmission circuit and a circuit connecting each source with the other transmission circuit for transferring energy to compensate for interaction between said transmission circuits, said transferring circuits including amplifying means.

14. An electric system comprising a plurality of adjacent transmission circuits, an alternating current supply source for each circuit and circuits connecting each source with the other transmission circuits for transferring energy to compensate for interaction between said transmission circuits, each transferring circuit including amplifying means.

15. A wireless transmitting system comprising a plurality of transmitting antennæ and means including an amplifier associated therewith for compensating for interaction between said antennæ.

16. A wireless system comprising a plurality of transmitting antennæ, a signal channel for each antenna and means associated with each antenna and the signal channels of the other antennæ for compensating the interchange between said antenna and the signal channels associated with the

other antennæ for interaction between said antennæ.

17. The combination in a radio signaling system of two transmitting antennæ in proximity to each other, a source of high frequency energy of one frequency connected to one antenna, a source of high frequency energy of a different frequency connected to the other antenna, and means for preventing an undesired reaction between the two antennæ by reason of the mutual capacity between them.

18. The combination in a radio signaling system of two transmitting antennæ in proximity to each other, a source of high frequency energy of one frequency connected to one antenna, a source of high frequency energy of a different frequency connected to the other antenna, and an inductive connection between the two antennæ for neutralizing the mutual capacity between them at one desired frequency.

19. The method of operating a radiating system comprising two adjacent transmitting antennæ, one having a source of high frequency energy of one frequency connected thereto and the other having a source of high frequency of a different frequency connected thereto, which consists in neutralizing the mutual capacity between the two antennæ for the frequency of one of the sources, and preventing undesired effects upon the antenna connected to the source of that frequency from currents set up in the other antenna.

20. The combination in a radio signaling system of two transmitting antennæ in proximity to each other, a source of high frequency energy of one frequency connected to one antenna, a source of high frequency energy of a different frequency connected to the other antenna, and means connecting the two antennæ for neutralizing the mutual capacity between them at one desired frequency.

21. A circuit arrangement comprising two senders having their antennæ electrostatically coupled, and arranged to operate simultaneously, and means for neutralizing the effect of the coupling between the antennæ with respect to a part only of one of the senders, said means comprising a circuit connected in parallel with said part and coupled with the other sender so as to receive compensating potential therefrom.

22. A circuit arrangement comprising two senders having their antennæ electrostatically coupled, and arranged to operate simultaneously, and means for neutralizing the effect of the coupling between the antennæ with respect to a part only of one of the senders, said means comprising a circuit connected in parallel with said part and including a coil coupled with a coil on the other sender so as to transmit compensating

potential from the last mentioned sender to said part.

23. In combination, a plurality of circuits having portions thereof coupled together, 5 means for neutralizing the effect of the coupling between said portions on a part only of any one of said circuits.

24. In combination, a plurality of circuits having portions thereof electrostatically 10 coupled together, inductive means for neutralizing the effect of the coupling between said portions on a part only of any one of said circuits.

25. In combination, a plurality of circuits 15 having portions thereof coupled together, one of said circuits having a part which it is desired to keep free from the disturbing influence of the coupling with another of said circuits, said part having a neutralizing 20 circuit connected across it and coupled with said disturbing circuit.

26. In combination, two transmitting circuits in proximity to each other, a source of high frequency energy of one frequency 25 connected to one circuit, a source of high

frequency energy of a different frequency connected to the other circuit, and means connecting the two circuits for neutralizing the mutual capacity between them at a desired frequency.

27. In combination, two circuits reactively related, local means for independently impressing an alternating potential across a portion of each of said circuits, and means interposed in circuit between circuits whereby interchange of energy, corresponding to the frequencies of the impressed potentials, between said circuits in either direction is prevented.

28. In combination, two grounded antenna 40 circuits operating at different frequencies and having mutual capacity, and a means interposed in circuit between said circuits whereby the capacitive reactance of said mutual capacity is neutralized for the frequency 45 of each of said circuits.

In witness whereof, I hereunto subscribe my name this 22nd day of November A. D., 1920.

HAROLD W. NICHOLS.
